UNITED STATES PATENT OFFICE.

GUSTAV B. PETSCHÉ, OF YONKERS, NEW YORK.

ROTARY PUMP.

1,380,013.

Specification of Letters Patent. Patented May 31, 1921.

Application filed September 25, 1920. Serial No. 412,821.

To all whom it may concern:

Be it known that I, GUSTAV B. PETSCHÉ, a citizen of the United States of America, and resident of Yonkers, county of Westchester, 5 State of New York, have invented a certain new and useful Improvement in Rotary Pumps, of which the following is a true and exact description, reference being had to the accompanying drawings, which form a part 10 thereof.

My invention relates to rotary pumps of the type in which the rotary piston is actuated by an eccentric and provided with a slide extending from one side through a swivel 15 block and the object of my invention is to provide a pump of this type in which the delivery passage is formed through the slide and provided with a non-return valve opening to permit the flow of fluid from the 20 pump and closed by contact with a stop supported on a fixed portion of the pump casing and preferably made elastically yielding.

The nature of my improvements will be best understood as described in connection 25 with the drawings in which they are illustrated and in which—

Figure 1 is a section on the line 1—1 of Fig. 2 of a pump provided with my improvement.

30 Fig. 2, a front elevation of the pump showing it as embodying two pumps opening into the same delivery chamber with the left hand pump shown in section on the line 2—2 of Fig. 1 with the piston and slide shown 35 in full.

Fig. 3 is an enlarged view of the slide and valve with certain preferable accessories not shown in Fig. 1, the view being taken partly in section.

40 Fig. 4 is a similar view of a modified construction of slide and valve.

Fig. 5 is again a similar view of another modified construction of slide and valve.

Fig. 6 is a cross sectional view on the line 45 6—6 of Fig. 5.

Fig. 7 is a face view of the gridiron valve shown in Fig. 5.

Fig. 8 is a view showing a modified construction of the device with which the valve 50 stem contacts to close the valve.

Fig. 9 is a view similar to Fig. 1 but showing the pump equipped with still another modified construction of slide and valve and of a different form of contacting device from 55 that shown in the former figures. The section is on line 9—9 of Fig. 2.

Fig. 10 is an elevation partly in section on line 10—10 of Fig. 9 similar to Fig. 2 but showing a modified device of Fig. 9.

Fig. 11 is a view on an enlarged scale of 60 the slide valve and valve actuating mechanism shown in Fig. 9.

Fig. 12 is a sectional elevation showing a preferred detail in connection with the construction shown in Figs. 9, 10 and 11, and 65

Fig. 13 is a view generally similar to Fig. 12 and showing the valve in closed position.

A and A' indicate two pump cylinders formed, as shown, in the same casing and having their outer faces closed by the face 70 plates A² and A³. A⁴ indicates the cylindrical surface of the pump cylinder. B is the bearing formed in the casing for the swivel block. B' is the delivery chamber of the pump connecting with an outlet passage in- 75

dicated at B². B³ is the inlet passage of the pump; C is a cover plate closing the passage of the chamber B'. C', Figs. 1 and 2, indicates metal bars preferably elastically yield- 80

ingly supported in line with the valve stem to be described. D is the driving shaft of the pump; D' an eccentric secured to this shaft. E is an eccentric ring piston making a line 85

contact with the cylinder surface A⁴. F is the slide attached to the eccentric ring and working in the guide slot formed in the swivel block indicated at M. F' is a delivery port opening through the lower portion of 90

the slide F and communicating with the passage F² formed through the slide and open- 95

ing into the delivery chamber B'. F³ is the valve seat formed in this passage and F⁴ is a guide formed in or attached to the slide in which works the valve stem. G is a valve 100 adapted to work in connection with the valve seat F³ having a valve stem G' which extends up upon the top of the slide in position to contact with the stop plate indicated at C'. The path through which the top of the valve stem will travel when in fully ar- 105

rived position is indicated at J and it will be obvious that the stop plate C' intersects this path and will cause the closing of the valve G when the slide is in the highest position. It will be obvious, of course, that this curve 110 will, under varying constructions of the pump, vary from the circular form shown.

In the construction shown in Fig. 3 a dash pot cylinder H is formed in the slide with restricted ports H' and H² opening from 110 its bottom and top and a piston I is secured to the valve stem G', this device serving

simply as a dash pot having the special function of securing the smooth working of the valve.

In the construction shown in Fig. 8 I have shown the spring bar C' as supporting the bearings C² of a roller C³ which roller forms the contacting surface for the end of the valve rod and saves it from wear.

In the construction shown in Fig. 4 I have shown a modified device in which the valve ports in the slide are formed in the cylindrical valve seat I, the ports being indicated at I' and opening into delivery passages F, F², the valve here of cylindrical form as indicated at J has ports indicated at J' formed through a downwardly extending flange of the valve, the construction being of the type known as a multiple ported piston valve. The somewhat modified guideways for the valve stem indicated at F² and shown at F, F⁴, and a somewhat modified dash pot cylinder is indicated at H, H. I have also shown in this view a ball bearing K held at the top of the valve spindle by clamps indicated at K', this device being, of course, merely for the purpose of diminishing friction.

In Fig. 5 I have indicated still another modification, the port leading through the lower side of the slide being indicated at f' and opening into a chamber L having a gridiron slide valve seat L' on its inner wall. The valve working on this valve seat is of the ordinary gridiron type indicated at g. The valve stem is indicated at g' and has attached to it a piston i working in a cylinder h which communicates through a pipe h' with the chamber L and through a restricted port H² with the delivery chamber at the top of the slide. f² indicates the passage through the slide.

In the construction shown in Figs. 9, 10 and 11, the slide is formed with a cylindrical guide f, f⁴ and the valve indicated at N having a short cylindrical stem N⁴ which fits in the lower portion of the cylindrical guide, also fitting and working in this cylindrical guide is the plunger indicated at O the top of which is swivel jointed to a rod P the upper end of which is again swivel jointed to an adjustable slide P' on the lower end of a screw P², P³ being a lock nut screwing on this thread. By preference I secure in the lower end of the cylindrical guide a spring holding cap indicated at N² in which the stem N' of the valve works and which supports a spring N³, as shown in Figs. 12 and 13, the spring permitting the valve to rise from its seat when the pressure of the delivery fluid becomes so great as to overcome the tension of the spring. I also provide in the top of the cap a restricted passage N⁴ and a similar restricted passage O' is formed in the plunger O. In this way what is in effect a dash

pot is provided for preventing the valve from striking too forcibly against its side or against the bottom of the guide. N⁵, Fig. 11, indicate the path through which a point on the top of the valve cap would normally pass were it not for the interruption of this path by the plunger O.

In operation, and referring first to the construction of Figs. 1, 2 and 3, it will be obvious that the fluid forced out of the pump by the rotating piston will pass through the port F' in the slide and raising the valve G from its seat, too rapid opening of the valve being prevented by the action of the dash pot cylinder H. As the slide moves upward through the swivel block during the last portion of the delivery stroke of the piston the top of the valve stem G' comes in contact with the plate C' so that at the end of the delivery stroke the valve G is closed, preventing any back flow of the fluid at the beginning of the new cycle and obviously as the piston moves across from right to left and works its next downward compression cycle the valve stem leaves contact with the plate C' so that the valve is in condition to open as soon as the pressure reaches the determined amount.

It will be noticed in the construction shown that the port F' is so located as to close up the wall of the swivel block at the end of the compression cycle. This, however, is not necessary with the valve construction shown and the port may remain open without interfering with the efficiency of the pump.

In the construction shown in Fig. 4 the normal position of the valve J is the closed position shown, the valve being held in this position by the receiver pressure on the top of the valve. As soon as the pressure of the fluid in the port F' exceeds the receiver pressure the valve will move upward and open the delivery ports to the channel formed through the slide. At the end of the upper movement of the slide the valve stem of the ball K at the top of the valve stem will contact with the plate C' or its equivalent closing the valve which will remain closed until the next compression cycle can raise the pressure in the port F'.

In the modified construction of Figs. 5, 6 and 7 the gridiron valve g is actuated by the cylinder and piston h and i. The pressure building up in the chamber L is connected to the bottom of the cylinder h through the pipe h' while the pressure in the receiver is connected to the top of the cylinder through the restricted port H². Obviously, when the pressure in the chamber L exceeds the receiver pressure the piston i will move up carrying with it and opening the valves g. The closing of the valve is effected by a contact plate C' in the same way as already described and it will

be obvious that by using a restricted port R^2 the actuating cylinder h will serve also as a dash pot cylinder.

In the construction shown in Figs. 9, 10 and 11 the valve N is opened as soon as the pressure in the port F' exceeds the receiver pressure, the opening movement of the valve being preferably checked by the devices shown in Figs. 12 and 13. As the slide F moves upward the plunger O approaches the cylindrical valve stem and finally contacts with it and closes the valve, the plunger and its connections with the fixed part of the casing as described being in a broad sense the full equivalent for the contact plate C' described in connection with the other figures of the drawing. The advantage of having the device P' and through it the plunger, adjustable from outside by the means described will be obvious as this way the valve can be caused to seat itself at the exact time and with the exact pressure most desirable.

Having now described my invention, what I claim as new and desire to secure by Letters Patent, is:

1. In a rotary pump comprising a cylinder, an eccentric ring piston and a slide extending from the piston through a swivel block, a discharge passage formed through the slide, a non-return valve for closing said passage, moving with the slide and arranged to open automatically to permit the fluid to pass from the pump into the re-

ceiver and a valve closing stop supported on a fixed position of the casing and located to contact with and close the valve at the end of each rotative movement of the piston.

2. In a rotary pump comprising a cylinder, an eccentric ring piston and a slide extending from the piston through a swivel block, a discharge passage formed through the slide, a non-return valve for closing said passage, moving with the slide and arranged to open automatically to permit the fluid to pass from the pump into the receiver, means for cushioning the movements of the valve and a valve closing stop supported on a fixed position of the casing and located to contact with and close the valve at the end of each rotative movement of the piston.

3. In a rotary pump comprising a cylinder, an eccentric ring piston and a slide extending from the piston through a swivel block, a discharge passage formed through the slide, a non-return valve for closing said passage, moving with the slide and arranged to open automatically to permit the fluid to pass from the pump into the receiver, and an elastically yielding valve closing stop supported on a fixed position of the casing and located to contact with and close the valve at the end of each rotative movement of the piston.

GUSTAV B. PETSCHE.
